UNITED STATES PATENT OFFICE.

BENJAMIN T. CARSON, OF RENSSELAER, NEW YORK, ASSIGNOR TO DU BOIS MACHINE
SHOP, INC., OF ALBANY, NEW YORK, A CORPORATION OF NEW YORK.

PISTON PACKING-RING.

1,188,622.

Specification of Letters Patent. Patented June 27, 1916.

Application filed December 14, 1915. Serial No. 66,684.

To all whom it may concern:

Be it known that I, BENJAMIN T. CARSON, a citizen of the United States, residing at Rensselaer, county of Rensselaer, and 5 State of New York, have invented certain new and useful Improvements in Piston Packing-Rings, of which the following is a specification.

The invention relates to such improvements and consists of the novel construction and combination of parts hereinafter described and subsequently claimed.

Reference may be had to the accompanying drawings, and the reference characters 15 marked thereon, which form a part of this specification. Similar characters refer to similar parts in the several figures therein.

The object of the invention is to provide a simple, strong and tight-fitting piston- 20 packing ring, particularly adapted for use in gas-engines and the like.

Figure 1 of the drawings is a view in perspective, showing a complete ring embodying my invention. Fig. 2 is a cross-section of the same taken on the broken line 2-2 in Fig. 1. Fig. 3 is a cross-section of the same taken on the broken line 3-3 in Fig. 1. Fig. 4 is a cross-section of the same taken on the broken line 4-4 in Fig. 1. 30 Fig. 5 is a plan view of the outer ring-member. Fig. 6 is a view in perspective of an intermediate portion of said ring-member. Fig. 7 is a view in perspective of the end portions of the inner ring-member.

Referring to the drawings wherein the invention is shown in preferred form, my improved ring comprises an inner ring-member, 1, cut or divided at 2, and an outer ring-member, 3, cut or divided at 4, said 40 ring-members breaking joints with each other.

The inner ring-member is provided with a rectangular external groove, 5, formed by an external flange, 6, extending along one edge of, and terminating in a plane substantially tangential to the body of said ring at the ends thereof, as shown at, 7.

The outer ring-member, 3, is rectangular in cross-section, adapted to occupy the 50 tangential groove, 5, in the inner ring-member; and it has opposite its point of division,

4, a lug, 8, the inner surface, 9, of which is in a plane substantially tangential to the inner surface of said inner ring-member. The longitudinal extent and area of the 55 plane surface, 9, on the flange, 8, is substantially equal to the longitudinal extent and area of the plane surface, 7, on the flange, 6, when the ends of the ring, 1, are forced together by their confinement within an engine-cylinder. The ring-member, 3, with its lug, 8, fully laps, and bridges the point of division, 2, of the inner ring-member; and the plane surfaces, 7, and 9, on the 60 respective ring-members, make sliding contact with each other as the ring expands or contracts.

The engagement of the surface, 9, with the surface, 7, effectively prevents relative rotation of one ring-member upon the other, 70 without materially weakening the ring, while substantially strengthening the middle portion of the outer ring-member. By the tangential arrangement of the surfaces, 7 and 9, on the respective rings, the tendency of ordinary movements of contraction and expansion to break the continuity of the outer surface of the ring is minimized. 75

I have shown the external groove, 5, formed by a single angle in the inner ring-member by means of a flange extending along one edge only of said ring-member; but for certain purposes of the invention, the cross-sectional form of the groove may be varied so long as the grooved ring-member 80 has along one of its edges a groove-forming flange terminating in tangential surfaces co-operative in the manner above described with a tangential surface on the inner surface of the lug on the complementary ring- 85 member which occupies the groove.

What I claim as new and desire to secure by Letters Patent is—

A piston-packing ring comprising a pair of divided ring-members breaking joints 90 with each other, one of said ring-members being provided with an external groove formed by an external flange extending along one edge of said ring-member, the ends of said flange terminating in a surface 100 substantially tangential to the body of said ring-member at the ends thereof, said other

ring-member being of a cross-section adapted to occupy said groove, and having a lug lapping the ends of said flange, said lug having a surface substantially tangential to the inner surface of its ring-member in sliding contact with the tangential surface on the ends of said flange.

In testimony whereof, I have hereunto set my hand this 8th day of December, 1915.

BENJAMIN T. CARSON.
